CLAIM

I claim the ornamental design for a collapsible ironing chest/bench, as shown and described.

DESCRIPTION

FIG. 1 is a perspective view of a collapsible ironing chest/bench shown with the attachments shown in a retracted position;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom view thereof; and,

FIG. 8 is a perspective view thereof with the attachments shown in an extended position.

The broken lines shown in the drawings are for illustrative purposes only and form no part of the claimed design.
